(51) LOC (7) Cl. 12-16

CLAIM

(52) U.S. Cl. D12/190

The ornamental design for a side skirt for a motor vehicle, as shown and described.

(58) Field of Search D12/190, 203, D12/181, 184; 280/163, 164.1, 169, 828, 848, 762, 768, 153.5; 296/196, 197, 209

DESCRIPTION

(56) References Cited

FIG. 1 is a perspective view of a side skirt for a motor vehicle showing my new design;
FIG. 2 is a front view thereof;
FIG. 3 is a top view thereof;
FIG. 4 is a bottom side view thereof;
FIG. 5 is an end view thereof; and,
FIG. 6 is an opposite end view thereof.
The rear surface of the side skirt of a motor vehicle contains no ornamentality and is not part of the claimed design. Accordingly, a rear view is not provided and any illustration of the rear surface in any of the Figures is hereby disclaimed.
